UNITED STATES PATENT OFFICE.

CHARLES S. BEATH, OF ESCANABA, MICHIGAN.

CIRCULAR SAWING MACHINE.

SPECIFICATION forming part of Letters Patent No. 243,833, dated July 5, 1881.

Application filed April 27, 1881. (No model.)

To all whom it may concern:

Be it known that I, CHARLES SMITH BEATH, of Escanaba, in the county of Delta and State of Michigan, have invented a new and Improved Sawing-Machine, of which the following is a full, clear, and exact description.

The invention consists of a circular saw mounted on a swinging gate, of a frame provided with a roller-table for the log or poles to be cut, and with an adjustable gage, which swinging gate is provided with pulleys for maintaining a uniform tension of the driving-belt, and is drawn inward by spiral springs, but is drawn outward, when the saw is to cut, by means of a rope or chain attached to the swinging gate and to a lever pivoted to the end of the frame and acted upon by a pivoted bent lever.

In the accompanying drawings, Figure 1 is a plan view of my improved sawing-machine. Fig. 2 is a longitudinal sectional elevation of the same on the line $x x$, Fig. 1. Fig. 3 is an end elevation of the same.

The circular saw A is rigidly mounted on the end of a shaft, B, journaled on the upper end of a swinging gate, C, pivoted to the base of the frame D of the sawing-machine.

A belt-pulley, E, is rigidly mounted on the shaft B, and a pulley, F, is mounted on the shaft pivoting the gate C to the frame D. This gate C is provided with two downward-projecting arms, G G, and on the shafts connecting these arms the pulleys H and J are mounted, the former at the middle of the arms G and the latter at the ends.

A driving-belt, K, passes around the pulleys E, F, H, and J, and around a pulley, L, on the shaft L' of the main driving-pulley M.

The journal-boxes of the shaft L' are attached to screw-rods N, by means of which the tension of the belt K can be adjusted.

The swinging gate C is drawn inward—that is to say, from the log-receiving table—by one or two spiral or other springs, O O, attached to the gate and to the frame D. A rope, chain, or belt, P, is attached to the front of the swinging gate C, and, passing through a staple, Q, or over a pulley at the front end of the machine, is attached to a lever, R, pivoted to the front end of the frame D. Another lever, S, is pivoted to the front end of the frame

D, and the lower curved end, S', of this lever rests on the lever R, as shown in Fig. 3. By drawing the lever S in the direction of the arrow a' the lever R will be depressed, as indicated by the arrow b', and the swinging frame C will be drawn forward, as indicated by the arrow c'.

The log-receiving table consists of two bars, T, connected by a series of rollers, U.

A gage to regulate the length of the blocks that are cut off is formed of a longitudinally-slotted bar, V, provided with a rectangular arm, W, at one end, and held on the frame D by the screws X, passing through the slot 65 of this bar V, and thus permitting of an adjustment of the gage.

A bar, Y, is held to the side of the frame D, outside of the saw and parallel with the same, by a series of arms, Z Z. Upon this bar that 70 part of the log that is being cut off rests, and consequently it will not be jammed against the side of the saw while the cut is being made. The block that is being cut rests on this bar B until the cut is completed, when it tilts and 75 drops.

The operation is as follows: The log rests upon the roller-table, and is pushed forward until its end rests against the arm W of the gage V, which has been previously adjusted 80 according to the size of the blocks desired. The log is at right angles to the saw, and if the lever S is drawn in the direction of the arrow a' the saw A will be moved forward in the direction of the arrow c' and will gradually 85 cut through the log. As soon as the lever S is released the springs O draw the gate back in the reverse direction of the arrow c', whereby the lever R is raised and the lever S swings back in the reverse direction of the arrow a'. 90 If the gate C swings forward in the direction of the arrow a', the pulley H is raised and the belt K would be slackened; but at the same time the pulley J is raised, and as this pulley presses against the belt K it draws the belt 95 taut again, and the tension of the belt is always maintained.

Having thus described my invention, what I claim as new, and desire to secure by Letters Patent, is—

1. In a sawing-machine, the combination, with the frame D, of the saw A, and a swing-

ing gate, C, provided with arms G, and of the pulleys E F on the gate C, and the pulleys H J on the arms G, substantially as herein shown and described, and for the purpose set forth.

5 2. In a sawing-machine, the combination, with the frame D, of the saw A, the swinging gate C, provided with arms G, the pulleys E F H J, the belt K, the pulley L, the shaft

L', the driving-pulley M, and the screw-rods N, for adjusting the journal-boxes of the shaft 10 L', substantially as herein shown and described, and for the purpose set forth.

CHARLES SMITH BEATH.
